UNITED STATES PATENT OFFICE.

RAYMOND C. PENFIELD, OF NEW YORK, N. Y.

BRICK-LIFTER.

1,265,106.

Specification of Letters Patent.

Patented May 7, 1918.

Application filed January 31, 1917. Serial No. 145,627.

To all whom it may concern:

Be it known that I, RAYMOND C. PENFIELD, a citizen of the United States, and resident of New York, county of N. Y., and State of New York, have invented an Improvement in Brick-Lifters, of which the following description, in connection with the accompanying drawings, is a specification, like letters on the drawings representing like parts.

My present invention is an improved apparatus for the handling of bricks in stacked units of the type shown in my prior Patent No. 1,205,562, and the object of the invention is to improve and perfect brick lifters of that type.

In my development of automatic brick lifters or setters adapted to handling large masses of stacked brick, such as in the setting of green brick in driers and kilns, or in the handling of the burned brick, it is very important to have the apparatus lift, transport, and release, a unit stack of brick without disturbing the formation of said stack. To this end I have devised apparatus as shown in my said patent, having a plurality of brick engaging fingers extending rigidly under the brick and being lifted and held in horizontal position irrespective of the load, through a sliding framework.

The apparatus of my said prior patent worked satisfactorily where the brick were piled evenly, but if the rows or courses of a unit stack were uneven in the horizontal plane of their lowermost surface, the said prior apparatus was apt to distort the stack somewhat because the brick engaging members were rigidly connected and when lifted maintained the same horizontal plane. In my present brick lifter I have obviated the difficulty just noted by providing automatic means which would enable each brick engaging arm or finger to adjust itself and consequently adjust the entire brick-lifting apparatus, to the configuration of the lower line of the brick stack, irrespective of the different settling or parts of said stack. This is particularly necessary in the case of a burned brick stack, as, during the burning, the rows of brick settle unevenly. Thus, if

a brick stack, whether of green brick or burned brick, was piled unevenly, or had settled unevenly, giving a somewhat wavy line to the lower courses, my present brick lifter would permit each of the lifting members to yield and thus accommodate the

height of said lifting members to the wavy or uneven surface of the bricks engaged thereby. Therefore, the entire stack would be lifted, transported, and released without the slightest disturbing or distorting of the stacked bricks, even though the latter had settled or was piled unevenly throughout. In the present apparatus I have employed the sliding frame feature of my said prior patent, and the four-point suspension feature which maintains the brick lifting apparatus level irrespective of whether loaded or unloaded. I may also utilize, with the present individually yielding brick lifting member or finger, any of the gripping devices to engage a foundation row of brick on which the stack may rest, which foundation row is spaced to receive a lifting finger, said devices not being herein illustrated.

Further features of the invention, novel combinations of parts, and details of construction, will be hereinafter more fully pointed out and claimed.

Referring to the drawings illustrating a preferred embodiment of the invention,

Figure 1 is a front view of my brick lifter;

Fig. 2 is a side view showing one of the independently yielding brick engaging arms or fingers in its lowermost position.

Referring to the drawings, the apparatus comprises an upper portion adapted to be connected with the lifting crane and preferably through a turntable connection, and a lower portion having fingers to slide under and lift the brick stack, together with means for a relative sliding movement between these two portions. The upper portion includes the horizontal plate 1, formed with a T-member or members 2 and with a pair of brackets 4 and 5, to which are secured the vertical frame portions 6, 6, and 7, 7. These vertically extending parts are united at their top by suitable bolts to plates 8 and 9 respectively, each of said plates having arms 10, 10, extending forwardly and carrying hook or eye members 11 and 11 bolted thereto, which members are the forward lifting bails or links for the apparatus. Corresponding lifting links 12 are bolted directly to the plate 8 and rearmost arm 6, as clearly illustrated in Fig. 2. Braces 13, 13 extend from the plate 1 to the upper portions of the frame 6. The horizontal plate 1 is perforated at a number of places throughout its length to permit the passage of depending

2 rods 14, 14, 14. Each rod has a cap 15 fitting thereover and a pair of check nuts 16 and 17 threaded onto the top of the rod, holding said caps in relative position thereto and each bearing upon an expansible spring 18 coiled about said rod and resting on the top of the plate 1. Each rod 14 is connected with the lower or yielding finger to be described, and a normal tension of the spring 18 is adapted to hold said fingers in their uppermost position, while permitting a downward yield under load. Each lifting finger being independently supported and controlled by the respective springs thus gives an independently lifting and yielding action for each finger.

Adjacent each rod 14 where the same passes through a hole in the plate 1, is secured a hollow sleeve 20, by a bracket 21 secured to the plate 1 by bolts 22, 22. I prefer to form the plate 1 with a lug 23 adjacent each of said brackets 21, so as to provide a guide and a rigid joint to facilitate assembling and increase the strength, as clearly delineated in Fig. 2. Each finger comprises a hollow casting 25 having a central recess adapted to fit over and slide loosely on the sleeve 20, said casting carrying a forwardly extending lifting member or finger 26. This finger 26 is preferably secured to the casting 25 by means of flanges 27 and 28 at one end, which flanges are secured to the casting 25 by bolts 29 and 30, or in any other suitable manner. This enables the lifting fingers 26 to be quickly replaced if one is broken and also provides an interchangeable construction of parts which will facilitate assembling the apparatus and minimize cost of manufacture. To counterbalance the finger 26 I provide a weight 31 secured to the casting 25 by a lug 32 and pin 33 (see Fig. 2). This balanced construction is desirable, as the entire casting 25 slides upon the sleeve 20 and insures automatic self-seating of each of the fingers 26 against the lower rows of the brick stack to be lifted, without binding or affecting the sliding action of the other fingers in the apparatus. To still further facilitate this sliding movement, I prefer to have roller bearings fitted within the casting 25, as clearly shown in dotted lines at 34, 35, and 36, Fig. 1, said rollers being properly fitted to bear upon the outer surface of the sleeve 20.

Each rod 14 extending within the hollow sleeve 20, has its lowermost end portion 37 formed as an eye and engaging the shaft or pin 38, which extends through slots 39 and 40 in the walls of the sleeve 20 so that said pin rigidly engages the casting 25. Thus the entire weight of the casting 25, fingers 26, and counterpoise 31 is sustained by the upward thrust of the spring 18 through said rod 14, normally holding the same at the upward limit permitted by the slots 39 and

40. Adjustment of the nuts 16 and 17 determines the power of the spring 18.

In the operation of the apparatus it is swung into position adjacent a brick stack, said stack being piled on studs, beams, or a foundation row of brick which are spaced to permit the sliding through of the fingers 26 under the stack. The apparatus is then lifted and each individual lifting finger 26 engages the bottom of the brick stack, which stack is indicated roughly in dotted lines at 41, Fig. 2, the spring 18 for each of said lifting fingers permitting an individual self-seating of each finger upon that portion of the stack engaged by it, irrespective of the horizontal plane of the lower stack surface. It is intended that the tension of each spring 18 will be sufficient to enable its finger 26 to carry its proportionate share of load before the shaft 38 strikes the lowermost limit of the slots 39 and 40 through which it passes, although in case of overload, the limit afforded by said slots would prevent the casting 25 from sliding entirely off the sleeve 20. By having each individual lifting finger 26 thus separately and yieldingly supported, the unit of brick lifted by my apparatus, will be held intact irrespective of the different settling of the brick throughout its length, as will be readily appreciated, and therefore the entire unit thus lifted and transported may be released without distorting the stack. The lifter automatically accommodates itself to the stack to be lifted instead of, as in prior lifters, making the lower plane of the stack conform to the plane of the lifting fingers. As above explained, in the case of burned brick after they are being taken from a kiln, the uneven settling throughout the kiln presents a varied or wavy horizontal surface in the lower part of each unit lifted.

My invention is further described and defined in the form of claims as follows:

1. Apparatus of the class described having provision to engage and lift a plurality of bricks in stacked formation, by engaging the bottom of the stack, comprising a plurality of horizontally positioned lifting fingers adapted to be positioned under the bottom of said stack and automatic means to control the lifting force of each finger independently of all other fingers.

2. Apparatus of the kind described, comprising a lifting frame, a plurality of laterally extending lifting fingers carried by said frame adapted to be positioned under the bottom of the stack, yielding connections between said frame and each of said fingers, whereby the initial lifting movement of the frame automatically actuates said yielding members independently of each other and automatically conforms the lifting fingers to the uneven surface of the bottom of the stack to be lifted.

3. Apparatus of the kind described, comprising a lifting frame, a plurality of laterally extending lifting fingers carried by said frame adapted to be positioned under the bottom of the stack, yielding connections between said frame and each of said fingers, providing an automatic independently self-seating of each finger on the adjacent part of the stack.
- 10 4. Apparatus of the kind described, comprising a vertically extending lifting frame, a plurality of laterally extending fingers, independent connections for each finger with said lifting frame, permitting an independent relative sliding movement between each finger and said frame, and means to substantially balance the weight of each finger on the moving portions.
- 15 5. Apparatus of the class described adapted to lift a stack of brick having the lower surface of the stack in an uneven plane without disturbing the said stack, comprising a lifting frame, means to maintain said frame in horizontal position, means to engage the bottom portion of the stack at a plurality of points, and automatic means to conform said plurality of engaging devices with the uneven plane of the bottom of the stack engaged thereby.
- In testimony whereof, I have signed my name to this specification, in the presence of two subscribing witnesses.

RAYMOND C. PENFIELD.
